ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-OPERATING MECHANISM.

1,154,039.

Specification of Letters Patent. Patented Sept. 21, 1915.

Application filed February 12, 1915. Serial No. 7,675.

To all whom it may concern:

Be it known that I, ISAAC H. MILLIKEN, a citizen of the United States, residing at Aspinwall, in the county of Allegheny and State of Pennsylvania, have invented certain new and useful Improvements in Coupling-Operating Mechanism; and I do hereby declare the following to be a full, clear, and exact description of the invention, such as will enable others skilled in the art to which it appertains to make and use the same.

My invention relates to that class of car couplers which are so applied to railway cars that they are capable of swinging or turning so as to permit them to move laterally in their carrier irons when the cars to which they are attached are passing around a curve; and the principal object of the invention is to provide simple, practical, convenient and easily operated devices which may serve both to unlock the coupler and to shift it laterally so as to bring it into proper coupling position when the car is upon a curve.

Further objects of my invention are to afford means whereby the power exerted by the operator to shift the coupler laterally may be effectively increased through the intervention of leverage devices; to provide means for enabling the operator to conveniently and efficiently effect an extended lateral shifting or displacement of the coupler; to provide means whereby the operator may, from the same position, shift the coupler laterally in either direction in the carrier iron; and to so construct and combine the several elements of the device that the positions of the parts may serve to indicate the approximate position of the coupler with respect to the longitudinal axis of the car upon which it is mounted.

In the drawing illustrating the preferred embodiment of my invention, the scope whereof is hereinafter pointed out in the claims, Figure 1 is a front elevation of a laterally movable coupler and devices embodying my invention, a portion of the end of a car to which they are applied being also shown. Fig. 2 is a detail plan view of certain of the parts illustrated in Fig. 1. Fig. 3 is a detail view, partly in elevation and partly in section on the line 3—3, Fig. 2. Fig. 4 is a view similar to Fig. 3, but illustrating the coupler unlocking and shifting devices

in a different position. Fig. 5 is a detail side elevation of one of the operating bars, its actuating lever and the fulcrum member for such actuating lever.

As the invention is generally applicable to 60 couplers designed to have a lateral movement with respect to their carrier irons it is to be understood that the details of construction illustrated in the drawings, although representing the preferred embodiment of the invention, are in no wise essential features of the invention in its broad aspect.

In the drawings, 1 indicates a coupler of a well-known type having a stem or shank 70 which may be provided with an opening 2 that is adapted to receive a pivot pin whereby the coupler may be connected to a railway vehicle so as to be capable of extended lateral swinging movements with respect 75 thereto. The coupler is provided with a lock 3 and with the usual pivoted knuckle 4, and is preferably supported near its forward end in the customary manner by a carrier iron 5 allowing it to shift laterally to the desired 80 extent.

The lock 3, which may be conveniently mounted to slide vertically in the coupler head, is preferably actuated to perform an unlocking movement by means of a vertically rotatable arm or finger 6 the outer end whereof projects into a pocket 7 formed in the upper end of the lock. By engaging the top wall 8 of the pocket 7 the actuating arm 6 when rotated upwardly is adapted to effect an unlocking movement of the lock, as will be readily understood.

The lock operating member 6 is actuated by devices which also serve as a means whereby the operator may shift the coupler laterally within its limits of movement to any desired position on either side of the longitudinal axis of the vehicle to which said coupler is attached. These devices preferably involve the employment of one 100 or more stiff, inextensible bars or members 9 which are movably mounted with respect to the coupler 1 so as to be capable of inducing an unlocking movement of the lock 3, and which are also adapted to impart to the 105 coupler either a pushing or a pulling force accordingly as the necessity of the case may require the operator to swing the coupler to one side or the other of its central position. As shown in the drawings, it is preferred to 110

movably connect the members 9 with the coupler 1 through the instrumentality of a revolute shaft 10 which is journaled in separated bearings 11 that are integrally united to the coupler and project upwardly from the upper surface of the head thereof. The shaft 10 may be conveniently retained in assembled position in the bearings 11 by means of cotter pins 12 that span the openings 10 through which the said shaft is assembled in said bearings. Between the journal bearings 11 the shaft 10 is provided with stops or shouldered portions 13 and 14 which are adapted to respectively engage the corresponding journal bearings and thus transmit to the coupler 1 such pulling or pushing forces as the operator may apply to either of the members 9 to move the coupler laterally in the desired direction.

20 The lock actuating arm 6 is preferably formed integral with the shaft 10 so that when the latter is rotated the arm 6 will execute a corresponding movement, thus causing the lock 3 to positively execute an unlocking movement.

25 In order to provide a connection between each of the slideable operating bars 9 and the shaft 10 such as will enable the coupler 1 to execute longitudinal and lateral or swinging movements without imparting any substantial lateral strains to said operating bars, it is preferred to form the ends of the shaft 10 with eyes 15 which receive the upturned inner ends 16 of the corresponding members 9.

30 Cotter pins 17 which extend through the ends 16 of the operating bars 9 and engage the upper faces of the corresponding eyes 15 may conveniently serve as a means for maintaining the integrity of the connection between the rods 9 and the shaft 10. As

35 shown more especially in Figs. 3 and 4, the apertures through the eyes 15 are preferably formed with flaring, segmental portions 18 and 19 which extend in opposite directions, whereby, as will be appreciated from an inspection of Fig. 4, either of the operating rods 9 may be independently rotated to cause a corresponding rotation of the shaft 10, and whereby also the operating rods 9 may be permitted to return to

40 normal position while the shaft 10, after having been rotated to cause the lock 3 to execute an unlocking movement, remains in a position corresponding either to the lock-set position of the lock or to the unlocked position of the lock when the knuckle is open.

45 The means which it is preferred to employ for both rotating and pulling or pushing the laterally extending operating rods or members 9 are as follows: The outer end of each of the members 9 is formed with perforated jaws 20 between which a lever 21 is pivotally secured by means of a pin 22.

50 When the coupler is in its normal position

the levers 21 hang vertically, their long arms extending downwardly in a position where they may be readily grasped by the operator, and their shorter arms extending upwardly and standing opposite the corresponding central pockets of members 23, which are rigidly secured to the end of the car at opposite sides thereof to serve, as will presently appear, as fulcra or abutments for their respective levers 21. When, therefore, the levers 21 are opposite the central pockets of the members 23 the operator is assured, without being under the necessity of exposing himself to danger by stepping in front of the coupler to make an examination, that the coupler is substantially in its central position. Similarly the position of the levers 21 with respect to the other pockets of the fulcrum members 23 visually indicate the corresponding laterally displaced positions of the coupler.

55 When the coupler is to be moved laterally from its central position the longer arm of one of the levers 21 is grasped by the operator and raised or turned upwardly and forwardly until the shorter arm of the said lever enters the middle pocket 24 of the corresponding abutment casting. This movement of the lever 21 causes a rotation of the adjacent rod 9 sufficient to unlock the coupler 1 or to cause the knuckle 4 to be rotated to open position when the coupler is equipped with knuckle opening mechanism, the inclined bottom of the pocket 24 arresting the rotatory movement of the lever 100 by which the unlocking of the coupler 1 is effected. With the lever 21 held in this raised position, the operator pulls or pushes upon it, as the necessary direction of movement of the coupler may require, such pull or push being transmitted to the adjacent operating member 9 and through the latter to the coupler 1. The force exerted by the operator to move the coupler laterally is increased in transmission to the coupler, the end of the shorter arm of the lever 21 fulcruming upon one or the other of the vertical walls of whichever pocket 24, 25 or 26, as the case may be, the lever 21 may extend into at the time. Should extreme lateral movement of the coupler 1 be desired or should the leverage obtained when the lever 21 is extending into the middle pocket 24 be insufficient to permit the operator to readily shift the coupler to the desired position, the coupler 1 may be moved laterally a portion of the required distance while the lever 21 extends into the pocket 24, after which the upper end of the lever 21 may be transferred to the appropriate one of the adjacent pockets 25 and 26, thus affording better leverage for inducing further movement of the coupler. Brackets such as 27 are preferably employed to support the operating rods or members 9 from the car body 130

in such manner that said rods may be capable of sliding, turning and swinging or oscillating freely. As shown in the drawings it is preferred to form such brackets integral with the adjacent fulcrum member 23.

5 I claim:

1. In mechanism of the character indicated, the combination with a coupler which is mounted upon a railway vehicle so as to be capable of lateral movement at its outer end with respect to said vehicle, of a locking device for maintaining the parts of the coupler in coupled relation, means for actuating the locking device to cause it to 10 assume an unlocked position, and means for moving the coupler laterally in either direction, each of said means being rotatably movable on a common axis and involving means common to both.

20 2. In mechanism of the character indicated, the combination with a coupler which is adapted to be connected to a railway vehicle so as to be capable of swinging movements with respect thereto, of a locking device for maintaining the parts of the coupler in coupled relation, and means extending 25 toward the side of the car for swinging the coupler in either direction, said means being rotatable upon an axis extending in 30 its direction of length to cause an unlocking movement of said locking device.

3. In mechanism of the character indicated, the combination with a coupler involving a locking device for maintaining the parts of the coupler in coupled relation, of means movably mounted on said coupler for actuating the locking device to cause it to assume an unlocked position, said means involving a plurality of members having a 35 40 jointed connection, and said jointed connection involving a member having an aperture provided with opposite segmental walls which flare in opposite directions.

4. In mechanism of the character indicated, the combination with a coupler involving a locking device for maintaining the parts of the coupler in coupled relation, of rotatable means for actuating the locking device to cause it to assume an unlocked 45 50 position, said means involving a plurality of members having a jointed connection, one of said connected members being mounted on the coupler, and said jointed connection involving a member having an aperture formed with a flaring segmental wall.

5. In mechanism of the character indicated, the combination with a carrier iron, of a coupler mounted on a railway vehicle so as to be capable of lateral movement with 60 respect to said carrier iron, of means for moving said coupler laterally, said means involving a lever which is adapted to engage a plurality of fulcra.

6. In mechanism of the character indicated, the combination with a carrier iron,

of a coupler mounted on a railway vehicle so as to be capable of lateral movement with respect to said carrier iron, and means for moving said coupler laterally, said means involving a slidable bar connected to said 70 coupler, a lever connected to said bar, and a means affording a plurality of fulcra for said lever.

7. In mechanism of the character indicated, the combination with a carrier iron, 75 of a coupler mounted on a railway vehicle so as to be capable of lateral movement with respect to said carrier iron, a locking device for maintaining the parts of the coupler in coupled relation, a bar which is movable laterally coextensively with the coupler and which is rotatable to effect an unlocking movement of said locking device and which is 80 slidable to effect lateral movement of said coupler, and a lever movably connected to 85 said bar.

8. In mechanism of the character indicated, the combination with a carrier iron, of a coupler mounted on a railway vehicle so as to be capable of lateral movement 90 with respect to said carrier iron, a locking device for maintaining the parts of the coupler in coupled relation, a bar which is rotatable to effect an unlocking movement of said locking device and which is 95 slidable to effect lateral movement of the coupler, a lever connected to said bar, and means affording a plurality of fulcra for said lever.

9. In mechanism of the character indicated, the combination with a coupler 100 mounted on a railway vehicle so as to be capable of moving laterally with respect thereto, of means for moving said coupler laterally, said means involving a lever, a member having a plurality of recesses each 105 adapted to receive one end of said lever, and means connected to said lever and adapted to transmit power to said coupler to move the same laterally.

10. In mechanism of the character indicated, the combination with a carrier iron, of a coupler mounted on a railway vehicle so as to be capable of lateral movements with respect to said carrier iron, a locking device for maintaining the parts of the coupler in coupled relation, a shaft revolvably mounted on said coupler head and provided with means for actuating said locking device, said shaft being also provided with means for communicating lateral movement 110 to said coupler, slidable and revoluble bars movably connected to said shaft and respectively extending toward opposite sides of the vehicle, levers respectively connected to said bars, and means affording a plurality of 115 120 fulcra for each of said levers.

11. In mechanism of the character indicated, the combination with a carrier iron, of a coupler mounted on a railway vehicle so as to be capable of lateral movement with 125

- respect to said carrier iron, a locking device for maintaining the parts of the coupler in coupled relation, a shaft revolubly mounted on said coupler head and being adapted to 5 actuate said locking device and being provided with means for communicating lateral movement to said coupler, slideable and independently revoluble bars connected to said shaft, and operating levers connected to 10 their respective bars, each of said bars being movably connected to said shaft by means involving an eye having a flared opening whereby either of said bars may rotate said shaft independently of the other bar.
12. In mechanism of the character indicated, the combination with a carrier iron, of a coupler mounted on a railway vehicle so as to be capable of lateral movement 20 within said carrier iron, bars connected to said coupler and respectively extending toward opposite sides of the car, means for slidably mounting said bars on the railway vehicle, leverage devices movably connected to the outer ends of the respective bars, and 25 fulcrum members for the respective levers, each of said fulcrum members being pro-

vided with a plurality of pockets for receiving the corresponding lever.

13. In mechanism of the character indicated, 30 the combination with a laterally movable coupler, of a fulcrum member having a plurality of pockets each of which is adapted to receive the end of an operating lever, and an operating lever adapted to be operatively connected to said coupler and to operate with said fulcrum member.

14. In mechanism of the character indicated, 35 the combination with a laterally movable coupler, of a member provided with a plurality of pockets each of which is adapted to receive the end of an operating lever, and also provided with a portion adapted to support a slideable bar, an operating lever adapted to enter the said pockets, and a 40 slideable bar operatively connecting said lever and said coupler.

In testimony whereof I affix my signature, in the presence of two subscribing witnesses.

ISAAC H. MILLIKEN.
